(57) **CLAIM**

The ornamental design for a display on head mounted display with graphical user interface, as shown and described.

DESCRIPTION

FIG. 1 is a front view of a graphical user interface for display on head mounted display; and,

FIG. 2 is a front view of the embodiment illustrated in FIG. 1 in which the third circle of the five circles illustrated on the left side of the design is highlighted.

The four icons on the upper right corner of FIGS. 1-2 (i.e., the “3G” icon, the signal strength icon, the battery charge icon and the time icon of “11:20”) illustrate environmental subject matter only and form no part of the claimed design.
